DESIGN FOR A TRUNK WARDROBE CABINET

Louis W. Skobel, Chicago, Ill., assignor to Interstate Metal Products Co., Chicago, Ill., a corporation of Illinois

Application July 13, 1936, Serial No. 63,822

Term of patent 14 years

To all whom it may concern:

Be it known that I, Louis W. Skobel, a citizen of the United States and residing at Chicago, county of Cook and State of Illinois, have invented a new, original, and ornamental Design for a Trunk Wardrobe Cabinet, of which the following is a specification, reference being had to the accompanying drawing forming a part thereof:

Figure 1 is a perspective view of my trunk wardrobe cabinet, in its closed position, showing my new design.

I claim:

The ornamental design for a trunk wardrobe cabinet as shown and described.

In witness whereof I affix my signature.

LOUIS W. SKOBEL.
